UNITED STATES PATENT OFFICE.

ROBERT E. CLARKE, OF JERSEYVILLE, ILLINOIS.

TRAY.

Application filed May 4, 1925. Serial No. 27,687.

My invention relates to trays and more particularly to a curb service tray for automobile, and, the invention is a distinct and practical improvement in curb service trays to overcome certain practical objections to, and defects in, the usual type of tray employed for curb service.

The object of my present invention is to provide a curb service tray adapted to be 10 removably supported by the door of an automobile body and positioned within the body so as to obviate the necessity of occupants of the vehicle holding a tray upon their laps, or holding a dish, glass or other article in their 15 hand, or hands while partaking of food, or drink at the curb of places serving refreshments, etc.

A further object of the invention is to provide a novel tray, and more particularly 20 an automobile curb service tray, but as is obvious, not necessarily limited thereto, which will possess advantages in points of simplicity, efficiency, durability and at the same time prove itself comparatively inexpensive in point of manufacture.

With the above and other objects in view, the invention consists in the novel features 25 of construction, arrangement and combination of parts hereinafter more fully described and finally pointed out in the claims hereto appended.

Referring to the accompanying drawings forming a part of this specification, wherein like characters of reference denote similar 30 parts throughout the several views:

Fig. 1, is a view in perspective of a tray embodying the features of my invention and shown as applied to a vehicle door.

Fig. 2, is a side elevation thereof, with 40 the tray proper shown in full lines in its open or serviceable position, and in dotted lines in its non-serviceable folded position.

Fig. 3, is a vertical sectional view of the device with a portion of the tray broken 45 away.

Referring to the drawings, the reference numeral 1 represents the door of an automobile, preferably a sedan, or coupé door with the glass panel or window 2 thereof in its 50 lowermost position, while the dotted lines 3 in Fig. 2 represent a roadster or touring car door of a motor vehicle.

In carrying out the aim of my present invention, I employ a suitable metallic tray 55 designated 4, which is preferably dished to provide the sides 5, the upper edges of

three of which sides, the front and two sides are turned or rolled outwardly and downwardly, as at 6, to obviate sharp edges, as is manifest. The rear side wall 5 of the 60 tray 4 is provided with a pair of extended sections or ears which are rolled or turned to provide hinge bearings 7. The tray may be enameled or otherwise finished to protect the metal and to add to its appearance. 65

The means for hingedly supporting the tray comprises a wire stand 8, which is bent at suitable equal points from the center of the stand and directed upwardly to provide the opposed door engaging arms 9, which 70 arms terminate at their upper end in the horizontally disposed inwardly and right angularly directed short door engaging shoulders 10. Each of the shoulders 10 terminate at their inner ends in the upwardly 75 and right angularly directed door engaging arms 11 which terminate at their upper ends in a looped head 12 to provide a resilient section for the tray holder to permit of expansion of the door engaging arms, as will 80 be apparent hereinafter. The ends of the loops opposite the upper ends of the door engaging arms 11 are bent outwardly and directed horizontally a short distance to provide the door engaging shoulders 13 85 which are disposed in parallel relation with the door engaging shoulders 10. The outer ends of the shoulders 13 are directed downwardly at a right angle to the shoulders 13 to provide door engaging arms 14, which 90 extend to a point opposite the stand section 8, at which point they are bent and directed laterally a short distance to provide the hinge pin sections 15 which are receivable in the hinge bearings 7, as clearly shown 95 in Fig. 1. The outer ends of the hinge pin sections 15 of the tray holder are bent and directed downwardly a short distance at an angle to the hinge pin sections 15, as at 16, and then the lower end of the short holder 100 sections 16 are bent and directed outwardly a short distance at a right angle thereto to provide the horizontally disposed tray engaging fingers 17. The short ends 16 and fingers 17 form L-shaped terminals for the 105 holder which engage the rear wall 5 and the bottom wall of the tray to support the tray in its horizontally disposed operative or service position, as shown in the several views in full lines and more clearly in Figs. 110 2 and 3.

All sections of the wire stand forming

the holder excepting those represented by the numbers 14, 15 and 16 are covered with an elastic or equivalent tube or covering 18 to prevent the holder from scratching the surfaces of a vehicle door or other element to which it can be detachably applied.

10 The lower ends of the door engaging arms or members 9 are curved slightly outwardly, as at 19, so as to widen the space between the door engaging arms 9 and 14 at the entering point, as is evident from Fig. 3.

15 It will be observed from Fig. 2 and more clearly in Fig. 3, that the door receiving space 20 formed between the arms 9 and 14 and shoulder 10 is wider than the door receiving space 21 within the bounds of the arms 11 and 14 and the shoulder 13. The former space 20 is occupied when the device is applied to sedan and coupé doors which 20 are rather thick, while the latter space 21 is occupied when the device is applied to a roadster or touring car door which is not as thick as sedan and coupé doors.

25 The space and passage designated 22 within the bounds of the loop 12 and the arm 11 and inner end of shoulder 13 is provided for the entrance of the glass panel or window 2 when it is not fully down, as shown in Fig. 1, but for any 30 reason is slightly elevated, as shown in dotted lines in Fig. 2. In Fig. 2, the sedan door is shown in full lines, and the roadster and touring car doors are shown in dotted lines to show the position of the holder as applied to the different styles of doors.

40 It is evident from Fig. 2, that the tray 4 can be moved to a raised or folded position so as to lie in parallel relation with the inner face of the door when not in use, or when applying or removing the device from a door and when removed from a door and not in use or for transportation purposes.

45 While I have described the device as a curb service tray, it is self evident and manifest that my detachable door tray is not only applicable to automobile doors, but it is practical to hang or apply the device to any suitable supporting means capable of entrance into any of the holder supporting spaces 20, 21 and 22.

50 The device is also practical for use as a serving table within the vehicle while touring, as it provides a convenient means for supporting refreshments, whether the vehicle is in motion, or standing still.

55 The many advantages of the herein de-

scribed invention will readily suggest themselves to those skilled in the art to which it appertains.

60

I do not wish to be understood as having limited myself to the exact details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make 70 any such changes, or modifications as may fairly fall within the scope of the appended claims when fairly construed.

65

What I claim is:

1. In a service tray structure for automobile doors, a single strand of wire bent to provide a pair of spaced parallel arranged hooks connected by the central portion of the strand of wire, the free ends of said strand of wire being bent and directed 75 in opposite directions to provide hinge pin sections, a tray, a hinge bearing formed at the rear edge of the tray and mounted upon said hinge pin sections and said hinge pin sections terminating in L-shaped supports 80 for the tray to rest upon when disposed in a serving position.

75

2. In combination with a service tray, a hanger bent at equal points from the center thereof and directed upwardly and then inwardly to provide two door embracing arms, said arms then extending upwardly to provide door glass engaging arms when the glass is partly raised, said latter arms terminating at their upper ends in curved 95 sections to provide spring sections, said curved spring sections terminating in outwardly directed arms, the inner ends of which at the junction of the spring sections are adapted to engage the door glass when the glass is partly raised, the outer ends of said outwardly directed arms terminating in downwardly directed door embracing arms, said door embracing arms having their lower ends bent outwardly to provide hinge 100 pin sections to which the rear edge of the tray is pivoted, and the outer ends of said hinge pin sections being bent downwardly and outwardly to provide L-shaped supports 105 for the tray to rest upon when disposed in a serving position.
